UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY TRAFFIC-CONTROLLING APPARATUS.

Application filed March 14, 1925. Serial No. 15,647.

To all whom it may concern:

Be it known that I, RONALD A. McCANN, a citizen of the United States, residing at Swissvale, in the county of Allegheny and State of Pennsylvania, have invented certain new and useful Improvements in Railway Traffic-Controlling Apparatus, of which the following is a specification.

My invention relates to railway traffic controlling apparatus, and particularly to apparatus of the type comprising governing means on a train controlled by an energy source also on the train, such as the usual headlight generator and which train carried governing means is also controlled by energy received from the trackway.

In at least one form of apparatus of the type described which has hitherto been suggested the train carried governing means normally requires the supply of energy both from said train carried source and from the trackway to prevent an automatic application of the brakes.

Apparatus has already been suggested however for cutting out the train carried governing means, that is, for rendering this means ineffective to apply the brakes when the train passes out of territory which is provided with trackway apparatus for positively controlling the train carried governing means provided the engineman takes suitable action.

One feature of my invention is the provision, in apparatus of this type, of means for permitting the brakes to be released after the train carried generator has been stopped and again started up, provided the apparatus was cut out before the generator was stopped.

I will describe two forms of apparatus embodying my invention, and will then point out the novel features thereof in claims.

In the accompanying drawings, Fig. 1 is a diagrammatic view showing one form of trackway apparatus for supplying energy to trains. Fig. 2 is a view, partially diagrammatic, illustrating one form of train carried apparatus for co-operation with the trackway apparatus shown in Fig. 1 and embodying my invention. Fig. 3 is a view illustrating a modified form of the train carried apparatus shown in Fig. 2 and also embodying my invention.

Similar reference characters refer to similar parts in each of the three views.

Referring first to Fig. 1, the reference characters 1 and 1^a designate the track rails of a stretch of railway track over which traffic normally moves in the direction indicated by the arrow. These track rails are divided, by means of insulated joints 2, into a plurality of track sections A—B, B—C, etc. The portion of track to the left of point B is provided with apparatus for supplying energy to trains, and this portion of the track may therefore be termed "positive control territory." The portion to the right of point B is not provided with such apparatus, and this portion of track may therefore be called "non-positive control territory."

Each track section is provided with a track relay designated by the reference character R, with an exponent corresponding to the location, and connected across the rails adjacent the entrance end of the associated section. Each track section is supplied with track circuit current from a track battery 5 connected across the rails adjacent the exit end of the section. Means are also provided for supplying each section in the positive control territory with alternating train controlling current. The immediate source of such train controlling current is a track transformer designated by the reference character T with an appropriate exponent, and having its secondary 4 connected across the rails of the associated section in series with the corresponding track battery 5. The primary 6 of each track transformer T is supplied with alternating current from a suitable source, such as an alternator M, over line wires 3 and 3^a.

The circuit for the primary of each track transformer is carried over a front contact 7 of the track relay R for the section next in advance. It is therefore plain that each track section in the positive control territory is supplied with alternating train controlling current when the section next in advance is unoccupied.

Adjacent the entrance end of the non-positive control territory are a pair of auxiliary conductors 8 and 8^a located in the trackway adjacent the rails 1 and 1^a, respectively. The conductors 8 and 8^a are connected in series and are constantly supplied with alternating current from secondary 9

of a step-down transformer D. The primary 10 of transformer D is supplied with alternating current from line wires 3 and 3^a, and the parts are so proportioned and adjusted that the current in conductors 8 and 8^a is of considerably greater magnitude than the train controlling current flowing in the rails in the positive control territory. The purpose of these auxiliary conductors will be explained in connection with the operation of the train carried apparatus.

Referring now to Fig. 2, the train carried apparatus comprises a relay G, which I will call the "main" relay, and which is controlled by energy received from the track way. For this purpose the train is provided with a pick-up device E comprising a pair of magnetizable cores 12 and 12^a arranged in inductive relation with the two track rails 1 and 1^a, respectively, and carried on the train in advance of the forward axle 11, as illustrated in Fig. 1. Core 12 is provided with a winding 13, and core 12^a is provided with a similar winding 13^a, the two windings 13 and 13^a being so connected that the voltages induced therein by alternating currents flowing in opposite directions in the two track rails at any instant are additive. These windings 13 and 13^a are connected, through suitable amplifying apparatus 14, with the terminals of main relay G. Relay G is therefore energized when the train occupies a portion of track which is being supplied with alternating current. This relay G controls governing mechanism comprising a polarized controller P, a pneumatic relay K, and a brake applying magnet L arranged to apply the brakes when de-energized. The polarized controller P comprises a magnetizable core 16 provided with a winding 17 and a pivoted armature 88 adapted to swing toward the left or toward the right, depending upon the polarity of the current supplied to winding 17. By means of a toggle spring 89, armature 88 is held positively in the position to which it is last moved.

Pneumatic relay K comprises a cylinder 24 containing a piston 25 biased to its lower position by a spring 26. Fluid pressure, usually air, is at times supplied to cylinder 24 beneath piston 25 by means of a valve 20 controlled by polarized controller P. The valve body 19 comprises a chamber 19^a constantly connected with a source of air pressure, not shown in the drawings, by means of pipe 21. When armature 88 of controller P is swung to the left, the lower side of piston 25 is exposed to atmospheric pressure through port 22, valve 20 and port 23, and the piston occupies its lower position. If, however, armature 88 is swung to the right, valve 20 is correspondingly shifted and air is admitted from chamber 19^a, through valve 20 and port 22 to the underside of piston 25,

driving this piston upward against the bias of spring 26. Piston 25 of relay K controls three contacts 56, 44 and 47, which are arranged to be open when the piston is in its lower position, and to be closed when the piston is moved upwardly.

The train carried apparatus further comprises a manually operable push button Q comprising a plurality of contacts normally biased to their lower positions by gravity but arranged when the push button Q is actuated to be moved into their upper positions.

Energy is supplied to polarized controller P and to magnet L from a suitable source, such as a generator H, which may be the usual headlight generator found on steam locomotives.

It will be noticed that a resistance 15 is included in circuit with relay G, and that this resistance is normally shunted by a contact 42 of push button Q, which contact is normally closed. When contact 42 is closed, relay G is energized if the train is on a portion of track which is being supplied with train controlling current. But if contact 42 is open, thereby placing resistance 15 in series with relay G, the current then supplied to the relay when the train occupies a section of track which is being supplied with train controlling current is not sufficient to energize the relay. If, however, with contact 42 open, the pickup device E is over the auxiliary conductors 8 and 8^a, the comparatively large current in these conductors induces a sufficiently large current in the pick-up device to energize relay G.

In explaining the operation of the apparatus, I will first assume that the train occupies a section of track which is being supplied with alternating train controlling current, and that push button Q is in its lower position. Resistance 15 is therefore shunted and the voltage induced in the pickup device E causes relay G to be energized. Current then flows from generator H, through wires 27 and 28, front contact 29 of relay G, wire 30, lower point of contact 31 of push button Q, wires 32 and 33, winding 17 of controller P, wires 34, 35 and 40, lower point of contact 36 of push button Q, wire 37, front contact 38 of relay G, and wire 39, back to generator H. The direction of this current is such that armature 88 of controller P is swung to the left, thereby allowing piston 25 of relay K to drop to its lower position and open the contacts associated therewith. Another circuit may be traced from generator H, through wire 27, front contact 49 of relay G, wires 50 and 51, brake applying magnet L, and wire 52 back to generator H. It is therefore plain that with push button Q in the position illustrated, as long as train controlling current is supplied to the section of track occupied by the train

the brake applying magnet is energized and the train is permitted to proceed without retardation. If, however, the supply of train controlling current to the rails should be interrupted, the resulting de-energization of relay G would interrupt the circuit for magnet L and a brake application would result.

I will now assume that the train passes from positive control territory to non-positive control territory. If push button Q is operated as the train is passing over conductors 8 and 8^a, relay G continues to be energized, as has already been explained, and a circuit is then completed from generator H, through wires 27 and 28, front contact 29 of relay G, wire 30, upper point of contact 31 on push button Q, wires 35 and 34, winding 17 of controller P, wires 33 and 32, upper point of contact 36 on push button Q, wire 37, front contact 38 of relay G, and wire 39 back to generator H. The polarity of the current then supplied to controller P is such that armature 88 is swung to the right, causing pneumatic relay K to close the contacts 47, 44 and 56 controlled thereby. Should the train leave conductors 8 and 8^a before push button Q is released, relay G will become de-energized and current will then flow from generator H, through wires 27 and 28, back contact 29 of relay G, wire 43, contact 44 of relay K, wires 45 and 34, winding 17 of controller P, wires 33 and 46, contact 47 of relay K, wire 48, back contact 38 of relay G, and wire 39 back to generator H. The current supplied to controller P over the circuit just traced is also of such polarity as to move armature 88 to the right and the armature is therefore held in its right hand position and relay K continues to be actuated. When push button Q is released, the closing of contact 54 thereof completes an auxiliary circuit for magnet L, from generator H, through wire 53, contact 54 of push button Q, wire 55, contact 56 of relay K, wires 57 and 51, winding of magnet L, and wire 52 back to generator H. It should be pointed out that this auxiliary circuit for magnet L does not include a contact on relay G, and that the train can therefore proceed without retardation although relay G is de-energized. Contact 56 remains closed because armature 88 is held in its right hand position until winding 17 of controller P is supplied with current of such polarity as to move armature 88 to the left.

Should generator H be stopped while contact 56 is closed, magnet L will, of course, be de-energized and the brakes be applied. When generator H is again started, however, current is immediately supplied over the auxiliary circuit for magnet L and the brakes can then be released. It should be particularly noted that the stop-

ping of generator H, although it de-energizes magnet L, does not affect the remaining apparatus, and that controller P continues to hold armature 88 in its right hand position. One condition under which this feature is valuable is when the locomotive carrying the train carried apparatus illustrated in Fig. 2 is temporarily withdrawn from service, as during the interval between runs, and the headlight generator is stopped. Under such conditions the locomotive is run into non-positive control territory, as into a round house. The train carried apparatus will therefore be "cut out," and controller P will be energized in the reverse direction to actuate relay K. When the generator stops, then, the brakes are applied, but contact 56 of relay K will be closed when air pressure is supplied to chamber 19^a. When the generator H is again started, magnet L will immediately become energized, and permit the brakes to be released.

I will assume that the apparatus has been cut out, as explained hereinbefore, so that relay G is de-energized, push button Q is in the position illustrated, and armature 88 of controller P is in its right hand position. Relay K is therefore actuated to close its contacts, and magnet L is energized over its auxiliary circuit. If, under these conditions, the train enters a stretch of track supplied with train controlling current, relay G immediately becomes energized, reversing the polarity of the current supplied to winding 17 of controller P. Armature 88 then swings to the left, and relay K opens its contacts, and interrupts the auxiliary circuit for magnet L. The closing of front contact 49 of relay G completes the main circuit for magnet L however and the parts are therefore restored to their normal conditions. The train is then permitted to proceed without retardation as long as the track occupied by the train is supplied with train controlling current.

Referring now to Fig. 3, in the modification here shown relay G is supplied with energy as in Fig. 2 from the pickup device E. The resistance 15 is normally shunted by contact 42 of push button Q, as hereinbefore explained, so that if the push button is in its normal position relay G is energized when a train occupies a stretch of track which is being supplied with train controlling current, but if push button Q is operated to open contact 42 relay G is energized only if the pickup device E is over auxiliary conductors 8 and 8^a. The polarized controller P is similar to the controller P of Fig. 2 but is further provided with a contact arranged to be closed only when armature 88 is swung to the right. The reference character J designates a stick relay comprising two windings 58 and 59. When push button Q is in its normal position and relay

G is energized, relay J is deenergized and current flows from generator H, through wire 60, front contact 61 of relay G, wires 62 and 63, back contact 64 of relay J, wire 65, winding 17 of controller P, wire 66, brake controlling magnet L, wire 67, back contact 68 of relay J, wires 69 and 70, front contact 71 of relay G and wire 72 to generator H. When this circuit is closed the 10 polarity of the current supplied to controller P is such that armature 88 is swung to the left, but magnet L is, of course, energized and the train is allowed to proceed without retardation. When the train passes over 15 auxiliary conductors 8 and 8^a and push button Q is operated to cut out the train carried governing means, a circuit is established from generator H, through wire 60, front contact 61 of relay G, wires 62 and 73, contact 74 of push button Q, wire 75, winding 58 of relay J, wires 76 and 70, front contact 71 of relay G, and wire 72 to generator H. Relay J therefore becomes energized. The 20 engineman then restores push button Q to its normal position and relay G becomes de-energized. A stick circuit is then established for retaining relay J in its energized condition as long as relay G remains de-energized. This stick circuit may be traced from generator H, through wire 60, back contact 61 of relay G, wires 77, 77^a and 80^a, front contact 80 of relay J, wires 81 and 82, winding 59 of relay J, wire 83, contact 84 of push button Q, wires 85 and 79, back contact 71 of relay G and wire 72 to generator H. Relay G now being de-energized and relay J being energized, current from generator H flows through wire 60, back contact 61 of relay G, wires 77 and 78, front contact 62 of relay J, wire 67, magnet L, wire 66, winding 17 of controller P, wire 65, front contact 64 of relay J, wire 79, back contact 71 of relay G and wire 72 to generator H. When this circuit is closed, the polarity of 40 the current supplied to controller P is such that armature 88 is swung to the right. Brake applying magnet L is, of course, energized and the brakes are released.

With the apparatus in this condition, I 50 will assume that generator H is stopped or for some other reason rendered ineffective to supply current to the train carried governing means. Relay J, of course, becomes de-energized, as does magnet L, and the 55 brakes are applied. Controller P, however, being last energized by current of such polarity as to swing armature 88 to the right, the contact controlled by this armature is closed, and when generator H is again 60 started or placed in service, current immediately flows through wire 60, back contact 61 of relay G, wires 77, 77^a and 87, contact 88 of controller P, wires 90 and 82, winding 59 of relay J, wire 83, contact 84 65 of push button Q, wires 85 and 79, back

contact 71 of relay G, and wire 72 to generator H. Relay J therefore becomes energized and is subsequently maintained in its energized condition over the stick circuit including its own front contact 80 as previously traced. Current is therefore supplied as explained hereinbefore to brake applying magnet L and to controller P. The 70 brakes are therefore released and controller P continues to be energized in such direction as to close contact 88 thereon. 75

Should the train enter a stretch of track which is supplied with alternating train controlling current, relay G would become energized, thereby interrupting the stick circuit for relay J, and allowing this relay to become deenergized. As a result the polarity of the current supplied to controller P would be reversed and contact 88 would be opened. Magnet L would, however, be energized over 80 front contact 61 of relay G and back contact 64 of relay J, and the train could proceed without retardation as long as relay G remained energized.

It should be pointed out that with apparatus embodying my invention if the train carried governing means has not been cut out by proper manipulation of push button Q as the receiving apparatus E passes over 90 conductors 8 and 8^a, the stopping of generator H will result in a brake application and that when the generator is again started the brakes will not be released because contact 88 of controller P will then be open and relay J cannot pick up. Under such conditions, therefore, it is necessary to energize 95 relay B before the brakes can be released. 100

Although I have herein shown and described only two forms of apparatus embodying my invention, it is understood that various changes and modifications may be made therein within the scope of the appended claims without departing from the spirit and scope of my invention. 105

Having thus described my invention, what I claim is:

1. In combination, a stretch of railway track having positive control territory equipped with primary means for supplying train controlling energy to trains and non-positive control territory not so equipped, auxiliary means located at the entrance to said non-positive control territory for supplying an excess of energy to trains, a first relay on a train for receiving energy from the trackway, a polarized controller controlled by said first train relay, and means on the train including said first relay and said polarized controller and responsive to energy from said auxiliary means but not to energy from said primary means for conditioning the train to proceed through said non-positive control territory without interruption. 115

2. In combination, a stretch of railway 120

track having positive control territory equipped with means for supplying train controlling energy to trains and non-positive control territory not so equipped, auxiliary means located at the entrance to non-positive control territory for supplying a greater amount of energy to trains, a circuit on a train receiving energy from both of said trackway means and including a 10 normally shunted resistance, a relay controlled by said receiving circuit and responsive to energy supplied in positive control territory when said resistance is shunted but not when the shunt is open, said relay 15 being responsive to the energy supplied by said auxiliary means when the shunt is open, governing mechanism controlled by said relay and normally requiring that the relay be closed to permit the train to proceed without retardation, a polarized controller controlled by said first relay and normally energized in one direction, manually operable means for simultaneously opening said shunt and energizing said polarized 20 controller in the opposite direction, and means controlled by said polarized controller and said manually operable means for rendering said governing mechanism ineffective to retard the train in non-positive 25 control territory.

3. In combination, a stretch of railway track having positive control territory equipped with means for supplying train controlling energy to trains and non-positive control territory not so equipped, auxiliary means located at the entrance to non-positive control territory for supplying a greater amount of energy to trains, a circuit on a train receiving energy from both of 35 said trackway means and including a normally shunted resistance, a relay controlled by said receiving circuit and responsive to energy supplied in positive control territory when said resistance is shunted but not 40 when the shunt is open, said relay being responsive to the energy supplied by said auxiliary means when the shunt is open, governing mechanism controlled by said relay and normally requiring that the relay 45 be closed to permit the train to proceed without retardation, a polarized controller controlled by said first relay and normally energized in one direction, a pin valve operated by said polarized controller, a normally open contact controlled by said valve and to be closed when the polarized controller is energized in the reverse direction, 50 manually operable means for simultaneously opening said shunt and energizing said polarized controller in the reverse direction, and means controlled by said manually operable means and by said normally open contact for rendering said governing mechanism ineffective to retard the train in non-positive control territory.

4. In combination, a stretch of railway track having positive control territory equipped with means for supplying train controlling energy to trains and non-positive control territory not so equipped, auxiliary means located at the entrance to non-positive control territory for supplying a greater amount of energy to trains, a circuit on a train receiving energy from both of said trackway means and including a 55 normally shunted resistance, a relay controlled by said receiving circuit and responsive to energy supplied in positive control territory when said resistance is shunted but not when the shunt is open, said relay 60 being responsive to the energy supplied by said auxiliary means when the shunt is open, a normally de-energized stick relay, manually operable means for simultaneously opening said shunt and supplying energy to said stick relay over a front contact of said first relay, a polarized relay, means for supplying such polarized relay with current of one polarity when said first 65 relay is energized but said stick relay is de-energized, means for reversing the polarity of the current supplied to such polarized relay when said first relay is de-energized and said stick relay is energized, governing 70 mechanism connected in series with said polarized relay and arranged to apply the brakes when de-energized, and means controlled by said polarized relay and by said first relay for energizing said stick relay.

5. In combination, a stretch of railway track having positive control territory equipped with means for supplying train controlling energy to trains and non-positive control territory not so equipped, a magnet on the train arranged when de-energized to apply the brakes, a generator on the train, means on the train requiring the continuous supply of energy from the trackway for connecting said magnet with said generator, and other means for at times connecting said generator with said magnet after the supply of train controlling current from the trackway is discontinued, said other means being effective if said generator is started after being stopped.

In testimony whereof I affix my signature.

RONALD A. McCANN.
